UNITED STATES PATENT OFFICE.

JAMES D. EDWARDS AND LEON FRANCOIS HAUBTMAN, OF NEW ORLEANS,
LOUISIANA.

SUGAR-DUMPING WAGON.

SPECIFICATION forming part of Letters Patent No. 296,544, dated April 8, 1884.

Application filed February 13, 1884. (No model.)

To all whom it may concern:

Be it known that we, JAMES D. EDWARDS and LEON F. HAUBTMAN, of New Orleans, parish of Orleans, Louisiana, have invented 5 certain new and useful Improvements in Sugar-Wagons, of which the following is a full, clear, and exact description.

The object of our invention is to provide certain new and useful improvements in sugar-wagons, to facilitate dumping the same.

The invention consists in a wagon-box provided at one end with means for hinging it, and at the opposite end with means for receiving a rope to lift the latter end of the box, and thus dump the box.

Our invention also consists in parts and details, as will be fully set forth and described hereinafter.

Reference is to be had to the accompanying 20 drawings, forming part of this specification, in which similar letters of reference indicate corresponding parts in all the figures.

Figure 1 is a longitudinal elevation of a sugar-wagon provided with our improvements, and 25 a sectional view of parts of the sugar-house. Fig. 2 is a plan view of the same, parts being broken out. Fig. 3 is a longitudinal sectional elevation of a wagon provided with modifications of our improvements.

The box or bin A is provided with the wheels 30 B, in the usual manner. On one end of the box two eyes or staples, C, are secured on the outer surface, and at the opposite end two apertured lugs, D, project from the upper edge 35 of the box.

On the edge of the trough E, into which the sugar is to be dumped, two standards, F, are secured, which are provided with eyes F' in the upper ends. A rod, G, is passed through 40 the eyes F', and through the eyes or staples C on the box, so as to form a hinge. Hooks G' are passed through the apertured lugs D, the said hooks being held on the end of a rope, H, passed over a pulley, J, and secured on the 45 drum of a windlass, K, whereby by winding the rope H on the windlass-drum the outer end of the box is raised and the contents of the box dumped to the trough E.

If it is not desired to have the eyes C 50 secured permanently on the box A, two bars, L,

are clamped on the box, which are provided with apertured lugs L', and at their lower ends with hooks M. A collar, N, having a downwardly-projecting prong, O, is mounted loosely on each bar L, the said collars being 55 provided with binding-screws P, for locking them in place on the bars. The hooks M are brought up against the bottom of the box A, the collars N are so adjusted that their prongs O project into the box, and then the collars are 60 locked in place, whereby the bars L will be clamped on the end of the car. The rod G is then passed through the apertures in the lugs L', and through the eyes F' in the standards F.

In place of providing the apertured lugs D, 65 tongs Q can be used, which are held on the ends of the rope H, the said tongs having a hook on the outer jaw and a plate on the inner jaw, the hooked jaw being adapted to catch on the rim-strip A' of the box A, as 70 shown in Fig. 3. A hook on the end of the rope H is passed through eyes formed on the upper end of the tongs-levers.

The standards F on the trough E are preferably made adjustable in height. 75

Having thus described our invention, we claim as new and desire to secure by Letters Patent—

1. The combination, with a wagon-box having eyes formed on one end, of standards at 80 the trough into which the contents of the box are to be dumped, which standards have eyes formed on their upper ends, and of a rod passed through the eyes on the end of the box and the eyes on the standards, substantially 85 as herein shown and described.

2. The combination, with a wagon-box, of bars provided with eyes or apertures, which bars are clamped on the end of the box, standards provided with eyes, and of a rod passed 90 through the eyes in the standards and the eyes on the bars clamped on the end of the box, substantially as herein shown and described.

3. The combination, with a wagon-box, of the bars L, having apertured lugs L', and 95 hooks M, the collars N, provided with the prongs O, and means for locking the collars on the bars, substantially as herein shown and described.

4. The combination, with a wagon-box, of 100

the eyes C, secured on one end, and the apertured lugs D on the opposite end, substantially as herein shown and described.

5. The combination, with a wagon-box provided with means for hinging it at one end, of means for securing a lifting-chain at the opposite end, substantially as herein shown and described.

6. The combination, with a wagon-box pro-

vided with means for hinging it, of the tongs Q, having a plate on the end of one jaw and a hook on the end of the other jaw, substantially as herein shown and described.

JAMES D. EDWARDS.
